SIGN ELEMENT AND METHOD OF
CONSTRUCTING THE SAMEEdward K. Madan, Maplewood, N. J., assignor to
Samuel Slutsky, New York, N. Y.

Application July 11, 1934, Serial No. 734,581

11 Claims. (Cl. 40—125)

This invention relates to the production of signs and various other types of displays for use in display or advertising purposes and to take the place of conventional illuminated signs and particularly such signs known as the neon signs; and the object of the invention is to provide a sign element which is composed of celluloid or other translucent material of any desired color or combinations of colors, and a mounting member 5 cut to conform with the outline of the sign element and to receive such sign element, the mounting member being of an opaque material whereby an artificial or other light disposed upon the rear face of the mounting member will illuminate that part of the sign element or elements arranged thereon to give the effect of a neon or similar sign; a further object being to provide each sign element with an extending flange or body portion providing means for securing the opaque mounting or background in connection therewith or to receive opaque members within the boundaries of the sign element; and with these and other objects in view, the invention consists in a sign of the class and for the purpose specified, which is made in accordance with the method herein more fully described and claimed.

The invention is fully disclosed in the following specification, of which the accompanying drawing forms a part, in which the separate parts of the improvement are designated by suitable reference characters in each of the views, and in which:

Fig. 1 is a face view of a mounting member showing one sign element coupled therewith with part of the construction broken away.

Fig. 2 is a partial section on the line 2—2 of Fig. 1.

Fig. 3 is a detail view of a mounting member indicating the step of cutting the same to receive a sign element.

Fig. 4 is a view showing a number of sign elements arranged on a mounting member; and,

Fig. 5 is a face view of a part of a frame showing a number of sign elements arranged therein.

For the purpose of illustrating a simple method of carrying my invention into effect, I have shown one or more sign elements made according to my invention in the form of the letters of the alphabet, but it will be understood at this time that my invention is not limited to sign elements of any particular shape or contour nor in the use of any particular number of such elements on or in connection with a suitable mounting member. In the construction shown in Figs. 1 and 2,

I have indicated at 10 a mounting member which is in the form of a heavy sheet of canvas or other fibrous material colored to give first an opaque appearance and secondly, a desired colored background suitable for and consistent with the complete display in the sign to be produced.

In Fig. 3 of the drawing, I have shown the method of shaping the mounting member 10 by die or otherwise cutting the letter B of the alphabet therefrom along the dotted lines indicated at 11, forming the peripheral contour of the letter B and along the lines 11a to form the inner field pieces 12 of the letter. The cut line 11 forms an opening 11b in the member 10 of the peripheral contour of the letter B. At 13, I have shown the letter B formed from a sheet of celluloid or similar semi-flexible material, the sheet being pressed outwardly to form a large beaded outline 14 of said letter with recesses 15 therein closed by the wall portions 15a upon which the field pieces 12 are secured to render the recesses 15 opaque in the resultant sign.

Extending from the peripheral walls of the beaded portions and in alignment with the walls 15a are outwardly projecting flanges 16 which overlie and rest upon the rear face of the mounting member 10 and to which the mounting member is secured by a suitable adhesive, preferably of the type commonly employed in connection with celluloid and similar material. This attachment may be made in the presence of heat and under pressure of an iron or die. In this connection, it will be understood that the sign elements may be made from any suitable translucent material capable of being shaped in accordance with the structure disclosed. The field pieces 12 are also secured in position by a suitable adhesive. The peripheral edges of the flanges 16 are parallel or substantially parallel to the edge of the sign element proper, thus maintaining the contour of the element as viewed from the rear of the mounting member.

The outwardly pressed beaded portions 14 of the sign element give the representation of a tube upon the outer surface of the mounting member, and in the use of the sign element, the placement of a light rearwardly of the mounting member 10 will operate to illuminate the beaded portions 14 of the sign element to produce a very attractive sign or display, and one which will represent or imitate the conventional neon signs, it being understood that the translucent sign element may be of any desired color and the color may be solid through the element, or in constructing the sign element from celluloid or other sheets of varie-

gated colors, a variegated colored effect may be produced in the resultant sign. In this connection, it will be further apparent that where a number of sign elements are used in conjunction with a single mounting member, the separate sign elements may be of contrasting colors to give contrasting ornamental effects on the complete sign or display.

In this connection, the element 13a in Fig. 4 mounted in connection with a backing 10a may be red in color whereas the sign element 13b, namely, the letter A of the alphabet may be blue, green, yellow or another color contrasting to that of the color employed in the letter B. Fig. 4 represents a partial view of what may be a continuous sign having any number of letters to spell out a word or a number of words and the entire sign may be contained in a suitable casing having a source of light supply for purposes of illumination.

In Fig. 5 of the drawing, I have indicated at 17 the outline of a frame, but in this frame the same is subdivided by partition strips 17a into a series of display openings 17b, 17c, in which separate backings 10b, 10c are arranged. The strips 17a serve to cover the abutting side edges of the backings 10b, 10c to form a neat and finished appearance on the front face of the sign. In this construction, each backing 10b, 10c has a sign element 13c, 13d, which in the construction shown are the letters B and A respectively.

With this type of construction, an interchangeable sign may be made, such for example as the signs of theatres where the head lines or advertising subject is changed from time to time. With this type of construction, by having an adequate supply of the respective letters of the alphabet, the signs may be readily changed from time to time.

Any desired type of backing may be employed and while it is preferred to have a backing which is opaque in character, there may be cases where a slight translucency would be provided in the entire field represented by the backing. In using a background of canvas or other fibrous material, the same may be cut on the bias or in the conventional manner, the latter being preferable in most cases, and it is important that the size of the boundary wall of the opening formed therein be equal to or possibly slightly less than the boundary of the display element so that said element will fit snugly therein, thus producing sharp and clean cut boundary edges to the display elements when in connection with the backing member.

In using sheets of relatively rigid material as mounting members, such for example as cardboard, sheet metal and the like, the openings formed therein will be made to freely receive the sign elements.

My improved device lends itself for use in connection with the skirt or flange portions of canopies or awnings, the lettering or other advertising matter being visible in the day time as with other sign elements, and being illuminated at night by the reflection of light from a store window or the like.

While I am aware of the fact that celluloid has been produced for the production of illuminated signs by reason of the translucency of the material, the distinctive feature of my invention resides in performing a mounting member to the contour of a display element formed from celluloid or other material, and to so shape the display element as to adapt its mounting in connection with the cut out portion of the mounting

member to provide in the resulting product a substantially unitary construction which will adapt itself to the manufacture of very economical signs and displays having unlimited uses.

While the letters of the alphabet alone are indicated for illustrative purposes, my invention is not limited in this respect as sign elements of any shape, form or contour may be employed to produce various types and kinds of displays or advertising members, and various changes in and modifications of the construction herein described may be made within the scope of the appended claims without departing from the spirit of my invention or sacrificing its advantages.

Having fully described my invention, what I claim as new and desire to secure by Letters Patent is:

1. A flat flexible sign comprising an opaque sheet of flexible fabric provided with spaced apart cut-out openings, each forming a letter and the letter-forming openings coating to form a word, a plurality of separate independent coverings, one for each cut-out opening, each covering comprising an integral, semi-flexible celluloid character of relatively light weight, having an attaching flange outlining the same and secured to the rear side of the fabric sheet about its respective opening and having a thin, translucent, character-forming, hollow, half-tube portion projecting from the plane of the securing flange, fitting in its associated cut-out opening and projecting forwardly beyond the front side of the fabric sheet, said sign having a relatively high degree of flexibility in the portions thereof between the characters and being semi-flexible in the portions formed by the characters and the word formed by the characters being visible from the front side of the sign and at a sharp angle to the plane of the sign both by light reflected from the front side of the characters and by light transmitted through the sides of the translucent, hollow, half-tube portions which project through the flexible fabric.

2. A flexible sign comprising a sheet of canvas provided with a line of cut-out openings, a plurality of separate, mutually independent coverings, one for each opening and secured to the rear side of the canvas, each covering comprising a pressed, letter-forming character of flexible sheet celluloid with a portion thereof being translucent, U-shaped in cross section and projecting through its associated opening, so as to be visible from the outer side of the sign, and the portions of the canvas between the coverings being flexible to form hinge joints between the word characters.

3. A sign comprising a sheet of canvas provided with an opening having a predetermined contour, an element for covering said opening comprising an integral, semi-flexible member of relatively light weight, said member having an attaching portion secured to the canvas sheet about its opening and having a hollow portion projecting from the plane of the attaching portion and of a contour corresponding approximately to that of the opening, said hollow portion registering with said opening and projecting beyond one side of the canvas sheet.

4. A sign comprising a body of semi-flexible fibrous material provided with an opening having a predetermined contour, an element for covering said opening comprising a semi-flexible sheet fashioned to form a hollow portion conforming substantially with the contour of the opening in said body, said element having attaching portions

at the periphery of the hollow portion, and means securing the attaching portions of said element to said body about the opening therein.

5. A sign comprising a mounting body of semi-flexible material provided with an opening having a predetermined contour, an element for said opening comprising a semi-flexible sheet fashioned to form a hollow portion substantially conforming with the contour of the opening in said 10 body, said element having attaching portions arranged upon said body about the opening therein, and said attaching portions being secured to said body by an adhesive and under applied heat and pressure.

15. 6. A non-rigid sign including a relatively opaque flexible mounting member, a semi-flexible symbol forming unit having a hollow symbol element of translucent material projecting from the plane of said unit, said mounting member having an opening substantially corresponding in contour to the hollow symbol element of said unit and registering therewith, with said member bordering the boundary edges of the symbol element, and that part of said unit extending from the boundary edges of the symbol element extending onto and being permanently secured to the bordering edges of said mounting member.

7. An article of manufacture of the class described comprising a mounting member of flexible material, a sign element composed of a sheet of semi-flexible, non-breakable material fashioned to form an offset hollow symbol projecting to one side of said sheet, said mounting member having an opening conforming and registering with the hollow symbol of said element, and means including a material set in the presence of heat, securing said element to adjacent portions of said mounting member.

8. An article of manufacture of the class described, comprising a mounting member of flexible material, a sign element composed of a sheet of semi-flexible material fashioned within boundary edges thereof to form an offset hollow symbol projecting to one side of said sheet, said mounting member having a cut-out opening conforming and registering with the hollow symbol of said element, means including a material set in the presence of heat securing the boundary edges of said element to adjacent portions of said mounting member about the periphery of said symbol, and said sign element including field pieces disposed inwardly of the boundaries thereof and of the same material as that of said mounting member.

9. The method of manufacturing signs of the class described, which consists in cutting from a sheet of fibrous material forming the mounting member of a sign an opening conforming with the contour of a predetermined sign symbol, shaping a sheet of semi-flexible material within the boundary edges thereof to form on one surface thereof a projecting symbol of a contour similar to that of the contour of the opening in said member, arranging said sheet upon said member to register the symbol with said opening with the boundary edges arranged upon the member bordering said opening, and then securing the edges of the sheet and member together by an adhesive and under applied heat and pressure. 15

10. The method of manufacturing signs of the class described which consists in forming in a sheet of fibrous material constituting the mounting member of a sign, an opening conforming with the contour of a predetermined sign symbol, shaping a sheet of semi-flexible material within the boundary edges thereof to form on one surface thereof a projecting symbol of a contour substantially similar to that of the contour of the opening in said member and with depressed portions within the boundaries of said symbol, arranging said sheet upon said member to register the symbol with said opening with the boundary edges arranged upon the member bordering said opening, securing the edges of the sheet and member together by an adhesive and under applied heat and pressure, cutting from the mounting member field pieces conforming with the outline of said depressed portions and arranging said field pieces in and securing the same to said depressed portions. 30

11. A sign comprising an opaque sheet of flexible fabric provided with spaced apart cut-out openings, each having a predetermined contour, a plurality of separate elements, one for each 40 opening, each element comprising an integral, semi-flexible celluloid member of relatively light weight, said member having an attaching flange outlining the same and secured to the rear side of the fabric sheet about its respective opening 45 and having a thin, translucent, hollow portion projecting from the plane of the securing flange and of a contour corresponding to that of its respective opening, said portion snugly fitting in said opening and projecting forwardly beyond the 50 front side of the fabric sheet.

EDWARD K. MADAN.
